UNITED STATES PATENT OFFICE.

WILLIAM M. VENABLE, OF PITTSBURGH, PENNSYLVANIA, ASSIGNOR TO BLAW-KNOX COMPANY, A CORPORATION OF NEW JERSEY.

BIN.

Application filed April 4, 1925. Serial No. 20,759.

This invention relates to bins and particularly to that type which has a hopper bottom through which the material stored in the bin is delivered.

5 One of the primary objects of my invention is the provision of a bin which can be easily assembled and taken down and is particularly useful in connection with work which involves the temporary storage of materials in the field.

Another object of my invention is the provision of a novel bottom arrangement for bins which is simple, easily assembled and permits of the use of a bin of other cross section than that of the hopper portion as for example a circular bin which is the most economical form.

A further object of my invention is the provision of a bin which can be supported by a simple form of support and in such manner that the whole weight of the bin and its load comes directly on the main members of the support.

These together with such other objects as may hereinafter appear, or are incident to my invention, I obtain by means of a construction which I have illustrated in preferred form in the accompanying drawings, wherein—

30 Fig. 1 is a vertical section through a bin embodying my invention;

Fig. 2 is a side elevation;

Fig. 3 is a plan view of Fig. 1 with the upper circular portion of the bin omitted;

35 Fig. 4 is a perspective view of one of the plates which form the bottom of the bin shown in Figs. 1, 2 and 3;

Fig. 5 is a plan view of another form of bottom construction embodying my improvements.

Referring now to Figs. 1 to 4 inclusive it will be seen that the bin is composed of an upper cylindrical portion A and a bottom B. The bottom is made up of plates having a 45 horizontal part 3 forming a ledge and a sloping part 4 forming a hopper. As best shown in Fig. 1 it will be seen that the horizontal ledge 3 constitutes a bottom for the overhanging cylindrical portion of the bin.

50 The support for the bin comprises a rectangular framework with upright members 5, the tops of which are secured to the horizontal channels 6 upon which the horizontal flange 3 of the bin bottom rests.

55 It will be seen that this method of sup-

porting the bin is extremely simple and economical. The entire weight of the bin rests on the horizontal members 6 and there is no necessity for providing any connections on the bin for the support and the weight of 60 the bin and material therein will be evenly distributed over the whole supporting framework.

In the form of support illustrated the opposite sides of the framework have been 65 trussed (see Fig. 2) in order to stiffen the construction. The ends of the framework may also be trussed in any desired manner but sufficient space should be left above the ground to allow for trucks and teams to 70 drive through underneath the hopper.

The bottom of the bin, illustrated in Figs. 1 to 3, is made of four plates. Two of these plates 9—9 (see Fig. 4) have a horizontal flange 3 approximately in the form of a 75 segment of a circle and a sloping portion 4 approximately in the form of a triangle. The sloping part 4 of these two plates is provided on each edge with an upstanding flange 10 preferably formed integrally with 80 the plate.

The other two plates 8—8 are similar in shape to the plates 9—9, the only difference being that the former have no flanges along the edge of the sloping portion 4.

To form the bin bottom these plates are assembled by riveting or otherwise securing the edges of the sloping portion of the plates 8 to the flange 10 on the plates 9.

The radial edges 14 of the horizontal 90 flanges 3 will abut in adjacent plates and form a tight joint.

It will be seen that the bottom of the overhanging cylindrical portion of the bin will be formed by the flanges 3, and that the remaining portion of the bottom of the bin will be formed by the hopper.

A gate 11 which may be of any desired construction is secured to the bottom of the hopper to regulate the flow of materials 100 therefrom.

In the construction shown in Fig. 5 I have illustrated a bin in which the hopper is hexagonal. The plates forming the hopper are of the same general shape as those shown in 105 Fig. 4. The principal difference between the plates in the two constructions is that in the hexagonal form each plate would be smaller for a given size cylindrical portion and also each plate is provided with a flange 12 along 110

one edge only thereof, the edge of the plate without the flange being secured to the flange on the adjacent plate.

It will be understood that the arrangement of the flanges 10 and 12 in the different constructions is optional as the arrangement shown in Fig. 5 could be used equally well in the construction shown in the other figures. If desired the flange could be entirely 10 separate in the form of an angle iron secured to both plates.

The cylindrical portion A of the bin may be of any convenient height and is formed of arcuate plates 15 which may be secured together in any desired manner. The diameter of this part A is slightly smaller than the diameter of the circle formed by the arcuate edges of the flanges 3 so that when the bin is assembled the horizontal portion of 15 the bottom will project slightly beyond the cylindrical portion A. Arcuate angle irons 16 rest on this projection and to these angle irons 16 the flanges 3 and cylindrical portion 20 15 of the bin are secured in any desired manner. The bottom A and upper part B are thus securely connected and held in position with respect to each other.

I claim:

1. In combination, a substantially cylindrical bin having a flanged polygonal hopper therebeneath, the flanges on the hopper forming a bottom for a portion of the bin.
2. In combination a substantially cylindrical bin and a flanged polygonal hopper therebeneath, said hopper comprising a plurality of sloping plates having flanges at the top which form the bottom for a portion of the bin.

3. In combination a substantially cylindrical bin and a flanged polygonal hopper 40 therebeneath, said hopper comprising a plurality of sloping plates having arcuate flanges at the top which form the bottom for a portion of the bin.

4. In combination, a substantially cylindrical bin having a flanged polygonal hopper 45 therebeneath, the flanges on the hopper forming a bottom for a portion of the bin, and supporting means for the bin upon which said flanges rest.

5. In combination a substantially cylindrical bin having a hopper therebeneath said hopper comprising a plurality of substantially triangular sloping plates having substantially horizontal flanges along the upper 55 edges thereof.

6. In combination a substantially cylindrical bin having a hopper therebeneath said hopper comprising a plurality of substantially triangular sloping plates having substantially horizontal flanges along the upper edges thereof and supporting means adapted 60 to engage said flanges.

7. A hopper for bins comprising a plurality of substantially triangular sloping plates 65 each having a substantially horizontal flange along the upper edge thereof.

8. A hopper for bins comprising a plurality of substantially triangular sloping plates each having a substantially horizontal 70 flange along the upper edge thereof and having a flange along another edge adapted to engage the adjacent plate.

In testimony whereof, I have hereunto signed my name.

WILLIAM M. VENABLE.
